[57] CLAIM

The ornamental design for a lawn golf mallet, as shown and described.

DESCRIPTION

FIG. 1 is a left side elevational view of a lawn golf mallet embodying my new design;

FIG. 2 is a left side elevational view of the same on a reduced scale;

FIG. 3 is a top plan view thereof;

FIG. 4 is a rear elevational view of the same with the handle broken away;

FIG. 5 is a bottom plan view thereof; and

FIG. 6 is a front elevational view thereof with the handle broken away.

A side elevational view taken from the side opposite that shown in FIG. 1 is essentially a mirror image thereof.
